MARCEL ZÜHLKE, OF BERLIN-WEISSENSEE, GERMANY, ASSIGNOR TO WESTINGHOUSE ELECTRIC & MANUFACTURING COMPANY, A CORPORATION OF PENNSYLVANIA

CHOKE COIL

Application filed September 4, 1930, Serial No. 479,614, and in Germany September 4, 1929.

My invention relates to improvements in choke coils and more particularly to choke coils constructed of flat sectional coils.

When a choke coil consisting of flat sectional coils of the construction hitherto known in the art, becomes hot in service, the heated air in the neighborhood of the coil system ascends. The cooling effect produced on the system by the rising air is, however, comparatively poor; the reason for this being, on the one hand, that a great part of the air put into motion by the heat does not come into contact at all with any of the heat emitting surfaces of the coil system and, on the other hand, that the rising air, so far as it does come into immediate contact with the coil system, only does so essentially on the outer and inner edges of the sectional coils but not on the surfaces of the flat coils where they face one another. For this reason and also because only a comparatively small part of the whole surface of the coil system can radiate heat outwardly, a considerable accumulation of heat takes place between the sectional coils.

According to the present invention, the above disadvantage which causes a comparatively very considerable reduction in the capacity of the choke coil, is eliminated by conducting the cooling air current through the apparatus in a special manner. A cooling air draft which can be advantageously produced by creating a "chimney effect", and may also be increased by the employment of a fan, is made to pass through the choke coil partly in radial and partly in axial direction, so that the cooling air comes into contact with all the heat-emitting surfaces, and particularly with the parallel faces of the coils. Besides, the best possible relation is obtained between the volume of cooling air passing through the apparatus and the size of the surfaces to be cooled.

In Figs. 1, 2 and 3 of the accompanying drawings, various constructions of choke coils of the above described kind are shown by way of example.

Fig. 1 shows a cross section of a single-phase choke coil constructed according to the invention; Fig. 2 is the top view of the coil.

The coil consists of four flat sectional coils s_1, s_2, s_3, s_4 above one another with openings n_1, n_2, n_3, n_4 in the middle. The individual coils are separated from one another by distance pieces c, d, e which may at the same time serve as insulation. They are held together and supported by bolts passing through feet i of insulating material. The opening n_1 of the bottom coil s_1 is closed by a closing piece u . On the top flat coil, is arranged a chimney-like extension a . Both the closing piece u and the chimney-like extension a may be made completely of a suitable insulating material, but it is mostly more practical to make the extension a of a non-magnetic metal coated with an insulating material. A choke coil of that kind represents altogether a kind of chimney, in which cooling air is constantly pressed through the interspaces between the sectional coils s_1, s_2, s_3, s_4 into the middle of the coil system, from where it flows off as warm air through the extension a into the open. In this manner, all the cooling current of air flowing through the system of coils is obliged to absorb heat produced in the windings, and at the same time all the surfaces emitting heat are exposed to a continual and uniform current of fresh air. The desired intensive cooling of the coil is thereby obtained.

In Fig. 3, a three-phase choke coil is illustrated, consisting of three groups g_1, g_2, g_3 of sectional coils. Between the individual groups, are arranged intermediate chimney-like parts z_1 and z_2 made of insulating material, or, if more advantageous for the particular case, of non-magnetic metal, coated with insulating material. The effect is in principle the same as with the aforescribed single-phase choke coil. The intermediate chimney-like pieces z_1 and z_2 may be made sufficiently strong to withstand the forces caused by short-circuits occurring in service.

In order to obtain a particularly intensive cooling effect with choke coils of this kind, the chimney-like extension may be made much longer than shown in the examples given in the drawings; it may also, for instance, be connected onto a flue.

If the existing conditions are particularly

unfavorable, the "chimney-effect" can be partly substituted by a fan built for example into the top extension *a*, as shown in Fig. 3 for the three-phase choke coil.

5. The decisive advantage of choke coils constructed according to my invention consists in that they are in the simplest manner made capable of carrying a considerably greater load.

10. I claim as my invention:

1. A choke coil, consisting of several flat sectional coils with an opening in the middle and arranged the one above the other at a certain distance from one another, means for supporting said sectional coils leaving room between these coils for a cooling medium to pass, and a closing piece, preferably of insulating material, fastened to the bottom sectional coil and closing the opening of this coil.

2. A choke coil, consisting of several flat sectional coils with an opening in the middle and arranged the one above the other at a certain distance from one another, means for supporting said sectional coils leaving room between these coils for a cooling medium to pass, a closing piece, preferably of insulating material, fastened to the bottom of sectional coil and closing the opening of this coil, and a chimney-like extension on the top sectional coil, said chimney-like extension consisting preferably of metal covered with insulating material.

3. A choke coil, consisting of several flat sectional coils with an opening in the middle and arranged the one above the other at a certain distance from one another, means for supporting said sectional coils leaving room between the coils for a cooling medium to pass, a closing piece preferably of insulating material fastened to the bottom sectional coil and closing the opening of this coil, a chimney-like extension on the top sectional coil, said chimney-like extension consisting preferably of metal covered with insulating material, and a ventilator in said chimney-like extension suitable for making a cooling medium pass between the individual flat coils and through the opening of these coils.

4. A choke coil consisting of several groups of flat sectional coils, said groups being arranged above one another, said flat sectional coils of each group having an opening in the middle and being arranged the one above the other at a distance from one another, means for supporting the individual coils, leaving room between these coils for a cooling medium to pass, a closing piece, preferably of insulating material, fastened to the bottom sectional coil and closing the opening of this coil, between the groups of sectional coils chimney-like intermediate pieces, preferably of non-magnetic metal, coated with insulating material.

5. A choke coil consisting of several groups

of flat sectional coils, said groups being arranged above one another, said flat sectional coils of each group having an opening in the middle and being arranged the one above the other at a distance from one another, means for supporting the individual coils, leaving room between the coils for a cooling medium to pass, a closing piece, preferably of insulating material, fastened to the bottom sectional coil and closing the opening of this coil, between the groups of sectional coils chimney-like intermediate pieces, preferably of non-magnetic metal, coated with insulating material, and on the top sectional coil a chimney-like extension preferably of metal covered with insulating material.

6. A choke coil consisting of several groups of flat sectional coils, said groups being arranged above one another, said flat sectional coils of each group having an opening in the middle and being arranged the one above the other at a distance from one another, means for supporting the individual coils, leaving room between these coils for a cooling medium to pass, a closing piece, preferably of insulating material, fastened to the bottom sectional coil and closing the opening of this coil, between the groups of sectional coils chimney-like intermediate pieces preferably of non-magnetic metal, coated with insulating material, on the top sectional coil a chimney-like extension, preferably of metal covered with insulating material, and in said chimney-like extension a fan suitable for making a cooling medium pass between the flat sectional coils and through the openings of this coil.

In testimony whereof, I have hereunto subscribed my name this 20th day of August, 1930.
